[57] CLAIM

The ornamental design for a baby stroller conversion unit, as shown and described.

DESCRIPTION

FIG. 1 is a top, front and side perspective view of a baby stroller conversion unit showing our new design, the opposite side is a mirror image of the side shown, and the rear view is plain and unornamented; and, FIG. 2 is a top, front, and side perspective view of an alternative embodiment of the baby stroller conversion unit showing our new design, the opposite side is a mirror image of the side shown, and the rear view is plain and unornamented.

The broken lines are for illustrative purposes only and form no part of the claimed design.
